UNITED STATES PATENT OFFICE.

STANLEY CHARLES BRYANT, OF CHICAGO, ILLINOIS, ASSIGNOR TO BRYANT ZINC COMPANY, OF CHICAGO, ILLINOIS, A CORPORATION OF ILLINOIS.

INTERLOCKING RELAY.

Application filed August 27, 1920. Serial No. 406,893.

To all whom it may concern:

Be it known that I, STANLEY C. BRYANT, citizen of the United States, residing at Chicago, in the county of Cook and State of Illinois, have invented certain new and useful Improvements in Interlocking Relays, of which the following is a specification.

This invention relates to interlocking relays for highway crossing signals and other 10 railway signaling systems.

The principal objects of the invention are to improve and simplify the construction of relays of this type, more especially with the view of obtaining greater accessibility of 15 the parts, reliable performance under the adverse operating conditions found in practice, and a cheap and simple organization of parts readily applied and used in conjunction with relays of commercial construction 20 and operating characteristics.

Detail features and advantages of my improved interlocking relay will appear hereinafter as the description progresses.

In describing the invention in detail, reference will be made to the accompanying drawing, in which:—

Figure 1 is a diagrammatic view in perspective showing the principal operating parts of an interlocking relay embodying 30 the invention, these parts being shown more with a view of making it easy to understand the general features of the construction and mode of operation, than with the object of showing the exact shape and arrangement of 35 parts preferably employed in practice;

Fig. 2 is a fragmentary side view of the interlocking mechanism;

Fig. 3 is a similar front view; and

Figs. 4 to 7 are detail views illustrating 40 the operation of the interlocking mechanism.

The invention in general resides in an interlocking mechanism designed for operation in connection with two neutral relays arranged end to end on a common base. The 45 construction of such neutral relays, being well known, has been shown conventionally. Referring to Fig. 1, these two relays A and B comprise the usual pair of cores 1 having enlarged pole pieces 2 and provided with the 50 usual windings or coils 3 (shown conven-

tionally); a back strap 4; and an armature 5. These cores are in practice supported upon the usual top plate of the casing (not shown) enclosing the armature 5, its contact fingers and associated parts. Each armature 5 is fastened to straps 6 which are pivotally supported on trunnion pins 7 fixed in depending lugs 8 secured to the top plate. Fastened to the armature 5 by insulating studs 9 are a number of contact fingers 10 (some of which are broken away to simplify the drawing), each having a pig-tail 11 to a binding post (not shown) and being adapted to cooperate with front and back contacts 12 and 13 shown conventionally as arrows. 60

My improved interlocking mechanism is made up of counterpart devices associated with the armatures 5 of the two relays A and B; and these parts are conveniently given the same designating numbers with the exponent "a" added. This interlocking mechanism comprises in general locking arms L and L^a, similar in construction and fastened one to each armature 5, and two hook-shaped latches or detents D and D^a. The locking 70 arms L and L^a stamped out of sheet metal, or formed in any other suitable way, have the peculiar shape shown, and are fastened at one end by screws or similar fastening means to the under face of its corresponding 80 armature 5 near the middle thereof. A counterweight 14 is provided for each locking arm to balance its weight about the axis of movement of its armature, so that the addition of said arm does not alter the operating 85 characteristics of the relay. Each locking arm L or L^a extends from the point of attachment to its corresponding armature sidewise substantially parallel with the front edge of said armature and above the contact 90 fingers 10, and then projects forwardly, where it divides into upper and lower bifurcations 15 and 16, each bifurcation terminating in a horizontal portion. These horizontal portions are located one higher than 95 the other, and in different vertical planes. The two locking arms L and L^a are slightly different in shape so that their upper bifurcations 15 overlap one above the other.

The latches D and D^a are each shaped, as 100

best shown in Fig. 2, to provide a holding projection or hook 17 having an upstanding tip 18, an operating shoulder 19, and a forwardly extending arm to which are secured 5 counterweights 20. These latches are pivotally supported on a pin 21 in the lower end of a hanger 22 which is fastened to the top plate by a screw 23 and cap washer 24 (see Figs. 2 and 3). The washer 24 has a cup or 10 depression around the screw 23 for putting in wax or the like to seal the device. The pivotal axis of the latches D and D^a is disposed vertically above the horizontal portion of the lower bifurcation 16 of the corresponding locking arm L of L^a; and these 15 latches are biased by the counterweights 20 to assume the position shown in Figs. 1 and 2.

Operation.—Normally, when both of the relays A and B are energized, the parts are 20 in the positions shown in Figs. 1 to 3. To facilitate explanation of the operation, one of the latches D, together with the upper bifurcation 15^a of arm L^a and lower bifurcation of arm L (the other bifurcations of 25 said arms being omitted to simplify the illustration), has been shown in Figs. 4 to 7 in the different positions they assume in the operation of the relay. When relay B is de-energized and its armature 5 drops, 30 the upper bifurcation 15^a of its locking arm L^a engages the shoulder 19 of the latch D and rocks this latch to bring its holding projection 17 under the lower bifurcation 16 of the locking arm L (see Fig. 5), so that when 35 the relay A is subsequently de-energized, its armature can not fully drop, because its locking arm is held up by the latch D, as shown in Fig. 6. When relay B is again energized, its locking arm L^a frees the latch 40 D, but said latch cannot return to normal because of the tip 18 (see Fig. 7). When relay A, however, is energized again, the latch D is released and swung back to its 45 normal position by its counterweight 20, all parts being now restored to their normal positions. The same sequence of operation occurs when relay A is de-energized first, the latch D^a being the one which is actuated in this case. Thus, the dropping of 50 either armature locks up the other armature and prevents it from dropping more than the short distance required for clearance between the latches D and the locking arms L, and further this locking continues until 55 said other armature again raises. The application of such an interlocking relay to the control of highway crossing signals and other devices is well known and need not be described.

60 It will be evident that my improved interlocking mechanism is simple and positive in its action, comprises few parts all of which can be cheaply manufactured and assembled, and further is so arranged and con-

structed that it can be readily applied to 65 commercial relay construction without material alteration or change in operating characteristics. The interlocking parts are near the front of the relay where they can be easily observed, and adjusted or repaired 70 when necessary.

Obviously the construction shown and described is susceptible of adaptation and modification in practice without departing from the invention, and I desire to have it 75 understood that my invention is not limited to the exact construction herein illustrated and described.

What I claim is:—

1. An interlocking relay comprising two 80 electromagnets having armatures hinged at the rear edge and arranged end to end and with their pivotal axes substantially in line, a plurality of insulated contact fingers attached to each armature, a bent locking arm 85 fastened to each armature and projecting forwardly with respect to said armatures, and two counterweighted hook-shaped latches pivotally supported on an axis substantially parallel with the pivotal axes of 90 said armatures and arranged to be actuated separately by the dropping of one arm to lock up the other arm.

2. An interlocking relay comprising two 95 neutral relays, a bifurcated locking arm secured to the armature of each relay, the bifurcations of each arm having upper and lower end portions moving in different vertical planes, and two counterweighted hook-shaped latches cooperating with said arms, 100 each latch being actuated by the upper bifurcation of one arm to lock up the lower bifurcation of the other arm.

3. Interlocking mechanism for relays comprising, in combination with two vertically movable arms, two latches pivotally supported and movable vertically in planes at right angles to the plane of movement of said arms, each of said latches having an operating shoulder and a hook portion with 105 an upstanding tip, said shoulder and hook portion of each latch being located on opposite sides of its pivotal axis.

4. An interlocking relay comprising, two 115 neutral relays arranged end to end with their armatures pivotally supported by a rear side, the pivotal axes of said armatures being substantially in line, two counterweighted latches pivotally supported in front of the armatures and substantially 120 midway between their adjacent ends, the axis on which said latches are pivoted being substantially parallel with the pivotal axes of the armatures, each latch having an operating shoulder and a hook portion with 125 an upstanding tip, said shoulder and hook portion of each latch being located on opposite sides of its pivotal axis, and a bifur-

cated locking arm secured to the armature of each relay, the bifurcations of each arm having upper and lower end portions, the upper end portions of one arm engaging the 5 operating shoulder of one latch upon dropping of the corresponding armature and rocking said latch to bring its hook portion

into position to hold up the lower portion of the other arm, whereby dropping of either armature prevents the full dropping 10 of the other.

In testimony whereof I affixed my signature.

STANLEY CHARLES BRYANT.
